UNITED STATES PATENT OFFICE

115,523

DESIGN FOR A COMBINED MOLDED PULP
CONTAINER AND COVER THEREFOR FOR
A FOOD PRODUCT, DRINKING CUP, OR
THE LIKE

Walter H. Randall, Waterville, Maine, assignor,
by mesne assignments, to The Canal National
Bank of Portland, Portland, Maine, a national
banking association, as trustee

Original application June 3, 1938, Serial No.
77,553. Divided and this application Decem-
ber 21, 1938, Serial No. 81,934

Term of patent 14 years

To all whom it may concern:

Be it known that I, Walter H. Randall, a citizen of the United States, residing at Waterville, in the county of Kennebec, State of Maine, have invented a new, original, and ornamental Design for a Combined Molded Pulp Container and Cover Therefor for a Food Product, Drinking Cup, or the like, of which the following is a specification, reference being had to the accompanying drawing, forming part thereof.

Fig. 1 is a perspective view of a combined molded pulp container and cover therefor for a food product, drinking cup or the like showing my new design, the cover being seated.

Fig. 2 is a similar view thereof with the cover displaced from its seat, and

Fig. 3 is a detail section on the line 3—3, of Fig. 2.

The characteristic feature of the design resides in the series of spaced raised ribs on the outer surfaces of the side and bottom walls of the container and the top surface of the cover, having the particular configuration and appearance as shown, the inner surfaces of the side and bottom walls of the container and the under surface of the cover being smooth.

This application is a division of Serial No. 77,553, filed June 3, 1938.

I claim:

The ornamental design for a combined molded pulp container and cover therefor for a food product, drinking cup, or the like, as shown and described.

WALTER H. RANDALL.
